DEVICE FOR IMPREGNATING FILAMENTARY
PACKAGES WITH LIQUIDS

Arthur B. Richardson and Donald C. Thompson,
Roanoke, Va., assignors to American Viscose
Corporation, Wilmington, Del., a corporation of
Delaware

Application May 16, 1942, Serial No. 443,314

11 Claims. (Cl. 68—206)

1

This invention relates to improvements for impregnating packages of filamentary material, particularly annular wound packages of artificial or natural filamentary material which are obtained by means of centrifugal spinning and twisting pots, such packages being generally referred to as "cakes," which term will be used hereinafter.

It is an object of the invention to provide a novel and improved form of liquid treating apparatus capable of treating a plurality of cakes of artificial filamentary material at once, of applying the liquid simultaneously to both the inside and the outside of the cakes and of yielding rapid and uniform impregnation thereof. Further objects of the invention will be apparent from the drawing and the description thereof hereinafter.

In the drawing, illustrative of the invention, Figure 1 is a side elevation, with parts cut away, of the device of the invention.

Figure 2 is an end elevation of the device with parts cut away.

Figure 3 shows the electrical connections diagrammatically.

Figure 4 shows a side elevation of a modification of a detail of the device.

Figure 5 shows an end view of such modification, and

Figure 6 shows an end elevation of part of the device with cakes thereon.

Figures 1 and 2 show the device without the cakes of filamentary material in position thereon. Essentially, the device comprises an upright standard 2 for supporting two horizontal tubes 3 and 4, preferably superimposed in a vertical plane. The upper tube 4 is provided with a plurality of spray heads along its under surface, each spray head comprising a single, or preferably, a plurality of orifices. The lower tube is also provided with a corresponding set of spray heads 5, preferably along its lower surface and a flange 6 is secured to the lower tube 3 just beyond the spray heads 5 in order to position the cakes to be placed thereon adjacent the sprays. A single conduit may serve to connect the supply of liquid to the several sprays in each of the rods. However, as shown in Figure 1, each spray head 5 may be connected by means of an individual line 7 to the distributor 8 connected to the liquid supply by means of a pipe 9 which is controlled by means of a valve 10. The standard 2 also supports a motor 11 which, through suitable connections, such as the worm 12 and gear wheel 13, a sprocket 14 and a chain 15,

2

drives a large sprocket 16 which is rotatably mounted upon a cylindrical portion of the lower tube 3 just back of the flange 6 secured thereto. This large sprocket 16 is provided with a socket 17 which is adapted to receive one end of a rod 18 by means of which an operator may insert the cakes to be treated into operative position within the device. The lower tube 3 has its upper surface indented to provide a longitudinal guideway 19 for the rod 18 to lighten the burden of the operator in loading and unloading the device with the cakes to be treated. A trough 20 is provided to catch any surplus liquid draining from the cakes during treatment and the trough 15 may have a discharge pipe 21 connected to a waste line or to the liquid supply so that the surplus drippings may be returned thereto.

The device as thus far described may be operated as follows: A loading rod having been removed with the previous batch of cakes, a fresh loading rod 18 carrying as many cakes as may be accommodated along the length of the spray tubes may be brought into position with one end resting upon the free end of the lower spray tube 3, the operator then sliding the loading rod up to the flange 6 and thereupon lifting the rod and inserting it into the socket 17 provided in the large sprocket 16. The operator thereupon pushes all of the cakes, which now embrace both the lower spray tube 3 and the rod 18, up against the flange 6, opens the valves 10 controlling the liquid supply line, and switches on the motor 11. Upon completion of one or more rotations of the rod 18 about the tube 3, the operator closes the valve 10 and switches the motor 11 off, unloads the cakes and repeats the cycle for subsequent batches.

Figures 4 and 5 show a modified form of lower spray tube 22 in which the flange 23 (analogous to flange 6 of Figures 1 and 2) secured thereto is slotted at 24 and a sloping trough like guideway 25 is secured to the tube to form a substantially continuous guiding surface from the grooved upper surface 26 of the spray tube to the socket 17 45 when it is in a position directly above the lower tube. By such a modification, the operator may simply stop the socket in its uppermost position and both unloading and reloading are greatly facilitated by means of the guideway 25 from the 50 socket to the lower tube.

In a preferred embodiment, the device is provided with electrical connections for automatically stopping rotation of the motor and closing the valve to the liquid supply when the socket 17 obtains its uppermost position. To accomplish

this result, the valve 10 in the fluid supply line may be a solenoid- or thruster-operated valve and a solenoid-operated brake may be provided upon the shaft of the motor. In addition, a switch 27 is provided whose two terminals 28 and 29 are adapted to be closed by contact with the outer periphery of the socket 17 at its uppermost position (see Figure 1). The arrangement is diagrammatically represented in Figure 3. The closing of this switch 27 by the socket 17 causes the main switch 30 connecting the motor and valve circuit to the power supply 31 to be opened, such as by the action of a solenoid 33 in the circuit with the socket switch 27 which retracts a core 34 and thereby permits the main switch 30 to spring open to the position shown in Figure 3. Assuming that the main switch 30 has thus been opened and a fresh batch of cakes has been loaded into the device, the operator starts the machine by closing the main switch 30 by hand or by a foot-operated lever and holding it closed until the socket 17 has passed out of contact with the terminals of the auxiliary switch 27. Closing of the main switch effects opening of the valve 10, operation of the motor 11, and a release of the brake 35 such as by operating a solenoid to retract suitable brake shoes from a brake drum on the shaft of the motor in opposition to springs normally tending to cause breaking. Upon completion of a single rotation of the socket 17, the auxiliary switch 27 is closed automatically by socket 17, thereby opening the main switch 30 which causes closing of the valve 10, and braking of the motor shaft.

If desired, the valve 10 may be replaced by a measuring pump which may be operated by an electric motor automatically controlled in the same manner as the valve 10 to start delivery of the liquid upon starting rotation of the cake supporting rod and to stop delivery upon each complete rotation of the rod.

While the device of the invention may be employed to apply any liquid to wound filamentary cakes, such as for bleaching, dyeing, etc., it is particularly adapted to the application of lubricating, softening, and conditioning media or solutions thereof, especially in organic solvents having low surface tension. The device has provision for applying the medium simultaneously from both inside and outside the cakes while moving the cakes relative to the liquid sprays. The result is an efficient, rapid and uniform impregnation of the cakes with a minimum of labor expenditure, power consumption and loss of material.

While preferred embodiments of the invention have been disclosed, the description is intended to be illustrative only, and it is to be understood that changes and variations may be made without departing from the spirit and scope of the invention as defined by the appended claims.

We claim:

1. A device for treating wound cakes of filamentary material comprising a longitudinal member supported adjacent one end only, a single socketed element mounted for rotation about said member adjacent the supported end thereof, and a portable carrier for said cakes consisting essentially of a substantially straight rod insertable into and removable from the socket for loading and unloading the device.

2. A device for treating wound cakes of filamentary material comprising a longitudinal member supported adjacent one end only, spray means thereon, a single socketed element mount-

ed for rotation about said member adjacent the supported end thereof, a portable carrier for said cakes insertable into and removable from the socket for loading and unloading the device, means for stopping said socket in a predetermined position above the longitudinal member.

3. A device for treating wound cakes of filamentary material comprising a longitudinal member supported adjacent one end only, spray means thereon, a single socketed element mounted for rotation about said member adjacent the supported end thereof, a portable carrier for said cakes insertable into and removable from the socket for loading and unloading the device, a second longitudinal member having spray means thereon, said member being arranged substantially parallel to the first member at a distance therefrom greater than the radius of rotation of the socket.

4. A device for treating wound cakes of filamentary material comprising a longitudinal member, a socketed element mounted for rotation about said member, a portable carrier for said cakes insertable into and removable from the socket for loading and unloading the device and means on said longitudinal member for guiding said portable carrier with cakes suspended therearound along said member.

5. A device for treating wound cakes of filamentary material comprising a longitudinal member a socketed element mounted for rotation about said member, a portable carrier for said cakes insertable into and removable from the socket for loading and unloading the device, means for stopping said socket in a predetermined position with respect to said longitudinal member and means on said longitudinal member for guiding said portable carrier with cakes suspended therearound along said member and into said socket in said predetermined position.

6. A device for treating wound cakes of filamentary material comprising a longitudinal member, a socketed element mounted for rotation about said member, a portable carrier for said cakes insertable into and removable from the socket for loading and unloading the device, means for stopping said socket in a position substantially directly above said longitudinal member, and means on the upper surface of said longitudinal member for guiding said portable carrier with cakes suspended therearound along said member and into the socket.

7. A device for treating wound cakes of filamentary material comprising a longitudinal member, spray means thereon, a valve for controlling the flow of liquid to said spray means, a socketed element mounted for rotation about said member, a portable carrier for said cakes insertable into and removable from the socket for loading and unloading the device, means for stopping said socket in a predetermined position with respect to said longitudinal member, means on said longitudinal member for guiding said portable carrier with cakes suspended therearound along said member and into said socket in said predetermined position and means associated with said stopping means for substantially simultaneously closing said valve when said socket reaches said predetermined position.

8. A device for treating wound cakes of filamentary material comprising a longitudinal member, spray means thereon, a valve for controlling the flow of liquid to said spray means, a socketed element mounted for rotation about said member, a portable carrier for said cakes insertable into and removable from the socket for load-

ing and unloading the device, means for stopping said socket in a predetermined position above said longitudinal member, and means associated with said stopping means for closing said valve.

9. A device for treating wound cakes of filamentary material comprising a longitudinal member, spray means thereon, a valve for controlling the flow of liquid to said spray means, a socketed element mounted for rotation about said member, a portable carrier for said cakes insertable into and removable from the socket for loading and unloading the device, means for stopping said socket in a position substantially directly above said longitudinal member, means on the upper surface of said longitudinal member for guiding said portable carrier with cakes suspended thereon along said member, and means associated with said stopping means for closing said valve.

10. A device for treating wound cakes of filamentary material comprising a longitudinal member, spray means thereon, a socketed element mounted for rotation about said member, a portable carrier for said cakes insertable into and removable from the socket for loading and un-

loading the device, a second longitudinal member having spray means thereon, said member being arranged substantially parallel to the first member at a distance therefrom greater than the radius of rotation of the socket, a valve for controlling the flow of liquid to said spray means in the longitudinal members, means for stopping said socket in a position substantially directly above said longitudinal member, means on said longitudinal member for guiding said portable carrier with cakes suspended thereon along said member, and means associated with said stopping means for closing said valve.

11. A device for treating wound cakes of filamentary material comprising a longitudinal member supported adjacent one end only, a single socketed element mounted adjacent the supported end of the member, and a portable carrier for said cakes consisting essentially of a substantially straight rod insertable into and removable from the socket for loading and unloading the device.
